(57) CLAIM

The ornamental design for a packaging carton, as shown and described.

DESCRIPTION

FIG. 1 is a perspective view of a packaging carton, showing our new design;

FIG. 2 is a front view thereof;

FIG. 3 is a rear view thereof;

FIG. 4 is a right side elevation view thereof;

FIG. 5 is a left side elevation view thereof;

FIG. 6 is a top view thereof; and,

FIG. 7 is a bottom view thereof.

The broken lines shown in the Figures depict portions of the packaging carton that form no part of the claimed design. The shaded portions shown in grayscale in the Figures illustrate a contrasting appearance between those shaded portions of the packaging carton and other portions of the PACKAGING CARTON shown without grayscale shading. The TruSkin logo shown in the drawings, and forming no part of the claim, is a registered trademark of TruSkin Partners Inc.
